UNITED STATES PATENT OFFICE

CHARLES WALLACE STARKS, OF BOISE, IDAHO, ASSIGNOR TO AUTOMATIC FOOD MACHINERY CORPORATION, OF BOISE, IDAHO

CONVEYER

Application filed May 15, 1930. Serial No. 452,679.

My invention is primarily intended for use in displaying and transporting foods, merchandise or any other articles in an endless procession and in a predetermined path past a display point.

The invention consists primarily of endless transfer elements having a plurality of carriages disposed thereupon and pivotally secured thereto. Means are provided for maintaining the carriages in a relatively horizontal position as they are transferred about sprockets disposed at the oppositely disposed ends of the display line.

A further object of my invention consists in providing means for ventilating the tunnel through which the endless conveyer passes in order to maintain the tunnel and the products disposed therein in a savory and sanitary condition.

20 A still further object of my invention consists in providing secondary endless conveyers disposed adjacent each side of the primary endless conveyer which preferably run in the opposite direction to that of the primary conveyer.

A still further object of my invention consists in maintaining the secondary endless conveyers in a sanitary condition.

Still another object of my invention consists in providing movable transparent top and side walls that comprise a part of the tunnel through which the primary conveyers pass in order to provide means for removing articles from either side of the tunnel way 35 and conveyer.

A still further object of my invention consists in providing means for regulating the temperature of the trays disposed upon and within the carriage units.

40 With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

50 In the drawings:

Fig. 1 is a fragmentary top plan view of the assembled device.

Fig. 2 is a fragmentary side view of the mechanism illustrated in Fig. 1.

Fig. 3 is a fragmentary sectional side view 55 of the power driven end of the assembled device which illustrates the means for transferring the carriages at the end of the display line, the same being taken on line 3-3 of Fig. 1 looking in the direction indicated. 60

Fig. 4 is a sectional end view of the assembled device, the same being taken on line 4-4 of Fig. 3 looking in the direction indicated.

Fig. 5 is a fragmentary sectional side view 65 of the assembled device, the same being taken on line 5-5 of Fig. 4 looking in the direction indicated.

Fig. 6 is a fragmentary sectional top plan view of the assembled device, the same being taken on line 6-6 of Fig. 5 looking in the 70 direction indicated.

Fig. 7 is a fragmentary sectional end view 75 of the top portion of the device, the same being taken on line 7-7 of Fig. 2 looking in the direction indicated.

Fig. 8 is a fragmentary sectional plan view of the assembled device, the same being taken on line 8-8 of Fig. 7 looking in the direction indicated.

Fig. 9 is a perspective side view of one of 80 the carriages shown removed from the device illustrating a removable top shown in the drawings as being in spaced relationship therewith to be used in conjunction with the carriage.

Fig. 10 is a longitudinal sectional side view 85 of a carriage having a removable receptacle which has a refrigerant fluid, or other cooling agency disposed therein in order to maintain the whole carriage assembly support and 90 the tray in a refrigerated condition.

Fig. 11 is a fragmentary sectional end view 95 of the assembled device illustrating the secondary conveyer cleaning mechanism, the same being taken on line 11-11 of Fig. 1 looking in the direction indicated.

Fig. 12 is a fragmentary sectional side view 100 of the driving end of the liquid-holding reconditioning vat through which the secondary conveyers are required to pass, the

same being taken on line 12—12 of Fig. 11 looking in the direction indicated.

Fig. 13 is a diagrammatical fragmentary sectional side view of the assembled device illustrating my new and improved device in use in transferring articles from one floor to another.

Like reference characters refer to like parts throughout the several views.

10 In preferred embodiment the invention consists of side walls 1 and 2. The side walls are preferably made of removable panel sections secured to fabricated posts 3 and 4. The structure is superposed, the fabricated frame consisting primarily of pairs of posts 5 and 6 with transparent movable panels 7 and 8 disposed between each pair of the superposed posts 5 and 6. A cross bar 9 is disposed upon the posts which ties the posts together transversely and acts as a support for a transparent top 10. The transparent top is preferably formed of panels of transparent material. Guides 12 and 13 upwardly extend and run longitudinally of the transparent top panels 10 forming side walls for protecting the transparent top panels. The side transparent panels 7 and 8 are vertically movable within guideways 14 and 15 that extend throughout the full length of the posts 5 and 6 and downwardly within the channelway formed by the side walls 1 and 2.

Pairs of secondary frames 16 and 17 outwardly extend from the posts 3 and 4 and channel ways 18 and 19 are formed upon the frames by having upturned walls 20 and 21 extending from their bottom. Panels 22 and 23 terminate the outer side of the frames 16 and 17 and run longitudinally thereof. Counters 24 and 25 are disposed upon the frame. The inner edge of each of the counter members is placed relatively flush with the outside of the post 5 and 6. Strips 26 and 27 run parallel to and are in spaced relationship with the counters 24 and 25 and lips 28 and 29 upwardly extend from the strips.

The primary conveyer consists of a pair of endless chains 30 and 31 which are trained about sprockets 32 and 33. The sprockets 32 and 33 are secured to stub shafts 34 and 35 which are journaled within suitable journal bearings as illustrated in Fig. 4. Sprockets 36 and 37 are secured to the respective stub shafts. A prime mover, as an electric motor 38, is disposed upon the base of the device and has a driving shaft 39 secured to its armature shaft 40 by any suitable flexible connection 41. A speed reducer 42 is adapted for being driven by the driving shaft 39 and the driven shaft 43 of the speed reducer has a sprocket 44 disposed thereupon. A jack shaft 45 is journaled and a sprocket 46 is disposed upon the jack shaft 45. A driving chain 47 is trained about the respective sprockets 44 and 46 and transmits power from the speed reducer 42 to jack shaft 45. Sprockets 48 and

49 are disposed upon the oppositely disposed ends of the jack shaft and driving chains 50 and 51 are trained about the respective sprockets 36 and 48 and 37 and 49 and in this manner power is transmitted from the jack shaft to the sprockets about which the primary endless conveyer driving chains are trained.

Four-wheeled carriages made as illustrated in Fig. 9 are secured to the chains 30 and 31. The carriage preferably consists of a fabricated structural frame having side walls 52 and 53 and end walls 54 and 55. Axle supporting corner plates 56, 57, 58 and 59 are secured to the fabricated walls. Axles are removably secured to the axle supporting corner plates and primarily consist of a body member about which the flanged wheels 60 are rotatably disposed. The axles have a head 61 disposed upon one end and a threaded terminal upon the oppositely disposed end to which a nut 62 is removably secured. The nut preferably is placed upon the inside of the corner plates to leave the outside of the axle substantially flush with the supporting wheel. These axles form journals for the flanged wheels 60. A pair of chain attaching and supporting plates 63 and 64 are centrally disposed upon the outside of each of the side walls 52 and 53 and the center lines of the axles and the chain engaging shafts lie in the same plane. Chain engaging shafts 65 and 66 are secured to the respective plates 63 and 64 and outwardly extend therefrom. These shafts are made to engage within the primary endless conveyer chains 30 and 31. The flanged wheels 60 which are preferably made of a non-metallic material in order to eliminate frictional noises, are required to ride within endless guideways 67, 68, 69 and 70. These guideways are preferably made of structural members and are disposed in direct alignment with the travel of the chains 30 and 31.

Timing sprockets 71 and 72 are disposed within the line of travel of the primary endless chains 30 and 31 which engage and drive these sprockets. A holding-down roller 73 is disposed over the center of the timing sprockets in order to maintain the chains in contact with the teeth of the timing sprockets. The timing sprockets are mounted upon stub shafts 74. Hubs 76A outwardly extend from one side of the timing sprockets and spiders 76 and 77 are secured to the hubs. Sprockets 78 and 79 are removably secured to the spiders. Recesses 80 are disposed in the outer periphery of these sprockets into which the flanged supporting wheels 60 are placed at the end of the line of travel of the carriages.

Cut-outs 81 and 83 are disposed within the structural guides 67 and 69, the cut outs 83 being adapted to having the shafts 65 and 66 pass therethrough and the cut-outs 81 being adapted to having the flanged wheels 60

pass therethrough. The flanged wheels on the forward end of the carriage are made to pass over the cut-out portions disposed within the structural members 67 and 69. The 5 passing of the flanged wheels disposed on the forward end of the carriage over the cut-out portions 81 is made possible because of the fact that the flanged wheels 60 and the shafts 65 and 66 lie in a common plane and 10 therefore so long as the shafts 65 and 66 and the flanged wheels disposed upon the rear of each of the carriages are held in a straight line, the flanged wheels disposed upon the front end of the carriage cannot be made to 15 enter the cut-out portions 81 but when the flanged wheels disposed upon the rear of the carriage reach the timing sprockets 71 and 72 and engage the recesses 80 disposed within the timing sprockets 71 and 72 the flanged 20 wheels disposed upon the front end of the carriage will enter the cut-out portions 81. The chain engaging shafts 65 and 66 are fixedly positioned to the primary chains 30 and 31 and the flanged wheels disposed upon the rear 25 of the carriage are engaged within the recesses 80. The flanged wheels disposed upon the forward end of the carriage engage within and follow the curved channel way 85. In view of this arrangement, the carriages 30 are at all times maintained in a horizontal position whether they are in the set of changing their direction or otherwise.

When it is desired to transfer the trays from one floor to another, the device may be 35 made as illustrated in Fig. 13 and when so made the flanged wheels disposed upon the forward end of the carriage enters the elongated channel way 86 and the chains 31 and 32 enter the elongated and parallelly disposed channel way 87.

I remove the chain supporting plates 63 and 64 from the carriage frame and place thereupon elongated plates 88 with two spaced stub shafts 89 and 90 outwardly extending 45 from the elongated plates 88 which also pass through the guide-way 87 to thereby maintain the carriage frame in a substantially horizontal position. It is necessary to provide fairly accurate fits between the guide-way 86 and the flanged wheels disposed upon the front end of the carriage and to provide fairly close fits between the stub shafts 89 and 90 and the guide-way to thereby cause the flanged wheels disposed upon the oppositely disposed end of the carriage to precisely engage within the recess 80 disposed upon the timing sprocket that is disposed upon the adjacent floor upon which the primary assembly of the device is to be placed.

60 When it is desired to maintain the articles to be conveyed by the carriage in a cold condition a liquid holding body element 91, as illustrated in Fig. 10, is provided into which cracked ice or a refrigerated solution, as 65 brine, may be placed therein and a tray 92

disposed thereupon. If it is desired to maintain the articles in a hot condition, the body element 91 is filled with a heated substance.

The secondary endless transfers 93 and 94 pass around driving drums 95. The driving 70 drums are adapted for being driven by the prime mover 95A. The endless secondary transfer belts pass between pairs of cleansing brushes 96 and 97 and over and under tightener pulleys 98 and 99 to thereby take 75 up any slack that may be developed within the belts. Vats 100 and 101 are placed so that the cleansing brushes and belts will contact a cleansing solution disposed within the respective vats. The purpose of this arrangement is to maintain the secondary transfer belts in a highly sanitary condition. A drain 102 acts as an outlet from each of the vats and the same is placed in registerable alignment and in spaced relationship with the 80 sewer drain 103. The treating solutions may be readily changed in the vat by the draining of the used solution therefrom and the replenishing of the same from any suitable source, not here shown.

In order to maintain the channelway through which the carriages travel in a ventilated condition, a suction fan 105 having a head 104 and driven by a prime mover 107 is disposed at the foot of the channelway and 65 an exhaust 106 removes the fumes from the vicinity of the device.

While the form of mechanism herein shown and described is admirably adapted to fulfill the objects primarily stated, it is to be 100 understood that it is not intended to confine the invention to the one form of embodiment herein shown and described, as it is susceptible of embodiment in various forms, all coming within the scope of the claims which follow.

What I claim is:

1. In a device of the class described, the combination of a fabricated framed structure, pairs of posts upwardly extending from the fabricated frame, transparent panels maintaining the pairs of posts spaced apart and slidably up and down relative thereto, a cross bar disposed upon the corner posts, transparent top panel elements supported upon the cross bar, guides disposed upon the posts having upturned legs to form positioning elements for the transparent top panels, pairs of secondary frames secured to the primary frame and outwardly extending therefrom and disposed at either side of the primary frame, channel ways disposed within the secondary frames, counters disposed upon the secondary frames, and strips disposed within the posts secured to the primary frame and having their upper surfaces disposed in registerable alignment with the counter and a lip upwardly extending from the inner edge of each of the strips.

2. In a device of the class described, the

combination of a carriage comprised of a fabricated frame, wheels journaled relative to the frame that are disposed at either corner of the frame and outwardly extending therefrom, a liquid holding body element disposed within the frame, a tray removably disposed within the liquid holding body element and forming a top therefor, means for attaching the carriage to an endless conveyer belt, and means for maintaining the carriage in a horizontal position throughout its line of travel.

3. In a device of the class described, the combination of a carriage, a pair of wheels disposed at either side of the carriage and journaled relative thereto, a liquid holding vat adapted for placement within the carriage, a tray removably secured to the vat and adapted for forming a cover therefor, means for securing the carriage to an endless conveyer chain to carry the same in endless procession and means for maintaining each of the carriages in horizontal position when a return in direction of travel is made by the chain, to change the direction of travel of the same.

4. In a device of the class described, the combination of a relatively long tunnel having a top comprised of transparent panels and having a plurality of panels forming the upper side wall of the tunnel, endless conveyer chains trained about sprockets mounted upon horizontal axles, said chains being power driven longitudinally of the tunnel, carriages secured to the chain and mounted in spaced relationship with each other disposed within the tunnel, means for maintaining the carriages in horizontal position during the return in direction of the chain, and means for ventilating the tunnel.

5. In a device of the class described, the combination of an elongated tunnel, endless chains disposed longitudinally of the tunnel and adapted for being driven therein, carriages secured in spaced relationship with each other upon the chain and adapted for being carried in horizontal endless procession through the tunnel, means for ventilating the tunnel, counters disposed at either side of the tunnel, and an endless conveyer disposed within each of the counters.

6. In a device of the class described, the combination of a tunnel comprised of transparent removable top panels and transparent panels forming the upper side walls, means for carrying carriages in endless procession and in horizontal position within the tunnel, an eating counter disposed at either side of the tunnel, a power driven endless conveyer disposed within each of the tunnels, means for maintaining each of the endless conveyers in a sanitary condition, and power means for ventilating the tunnel.

7. In a device of the class described, the combination of a fabricated frame comprised

of side and end walls, supporting corner plates downwardly extending from the fabricated frame, axles removably and fixedly positioned within the supporting corner plates, flanged wheels rotatably disposed upon the axles, pairs of chain supporting plates secured to the side frames and downwardly extending therefrom, and chain engaging shafts outwardly extending from the chain supporting plates, the center line of the axles and of the chain engaging shafts lying in a common plane.

8. In a device of the class described, the combination of a fabricated frame, a liquid holding body element disposed within the fabricated frame, a tray removably placeable and adapted for being supported by the liquid holding body element, axle supporting corner plates downwardly extending from the fabricated frame, wheels secured to the axles, a chain supporting plate downwardly extending from each of the side walls of the frame, and chain engaging shafts secured to the chain supporting plates and outwardly extending therefrom, the chain supporting shafts being equidistant from the axles disposed upon the same side of the frame, a line extending through the center line of the axles and the chain supporting shaft lying in a common plane.

9. In a device of the class described, the combination of a tunnel, counters disposed at each side of the tunnel, an endless conveyer disposed within each one of the counters, power driven endless chains disposed within the tunnel, a plurality of carriages disposed in spaced relationship upon the chains, guideways for said carriages, means for placing articles upon the carriages, means for ventilating the tunnel, means for cleaning the endless conveyers disposed within each of the counters, and means for maintaining the carriages in a horizontal position when changing direction from horizontal to vertical and back to horizontal.

10. Apparatus as in claim 9 including means for securing each of the carriages to the power driven endless chains.

11. Apparatus as in claim 9 wherein the tunnel is made of fabricated and transparent materials.

12. Apparatus as in claim 9 wherein the carriages are adapted to hold a temperature controlling substance.

13. Apparatus as in claim 9 wherein the guideways have a number of cut outs at the end of the line of travel of the endless chains.

CHARLES WALLACE STARKS.
